Inventor:
Alvin C. McCord,
By his Attorney,

William Merchant

UNITED STATES PATENT OFFICE.

ALVIN C. McCORD, OF CHICAGO, ILLINOIS.

MAIL-CRANE.

No. 884,407.

Specification of Letters Patent.

Patented April 14, 1908.

Application filed October 31, 1907. Serial No. 400,007.

To all whom it may concern:

Be it known that I, ALVIN C. McCORD, a citizen of the United States, residing at Chicago, in the county of Cook and State of Illinois, have invented certain new and useful Improvements in Mail-Cranes; and I do hereby declare the following to be a full, clear, and exact description of the invention, such as will enable others skilled in the art to 10 which it appertains to make and use the same.

My present invention has for its object to provide a simplified and generally improved mail crane and to this end it consists of the 15 novel devices and combinations of devices hereinafter described and defined in the claims.

More particularly stated, the invention relates to mail cranes, the bag-holding arms 20 of which are adapted to be locked in position to deliver the bag supported thereby, to a passing train, and then to automatically swing into position out of the way of passing trains.

25 The accompanying drawings show the improved mail crane.

In these drawings like characters indicate like parts throughout the several views.

Referring to the drawings, Figure 1 is a 30 view in elevation, showing the improved crane and a mail-bag held by the arms thereof in position to be delivered to a passing train. Fig. 2 is a view partly in elevation and partly in vertical section, showing the 35 lower part of the crane, the upper portion thereof being broken away. Fig. 3 is a detail in elevation, illustrating particularly the cam or spiral connection between the fixed and movable sections of the crane, the said 40 parts being viewed in opposite direction from that in which they are shown in Fig. 1; and Fig. 4 is a detail in horizontal section, taken on the irregular line $x^4 x^4$ of Fig. 2.

The relatively fixed section of the crane is 45 in the form of a tubular standard 1, the lower end of which, as shown, is secured to a base 2, which, in turn, is adapted to be rigidly secured to a station platform or other suitable support at the side of a railway track. To 50 the upper end of the tubular standard 1 is rigidly secured a sleeve-like cam head 3 which has a spiral cam groove 4 and constitutes part of the complete standard.

The movable section of the crane is made 55 up of a mast 5 and a pair of arms 6 and 7. The upper arm 6 is rigidly secured to the

upper end of the mast, as shown, by means of an elbow coupling 8 and an oblique bracket 9. The lower arm 7, at its inner end, is pivoted to a bearing 10 that is rigidly secured 60 to the intermediate portion of the mast 5. At their outer ends, the arms 6 and 7 are provided with rigidly secured fingers 11 and co-operating spring fingers 12, which fingers co-operate to form yielding grapples that are 65 adapted to detachably hold rings 13 that are applied in the usual or any suitable way to the upper and lower ends of the mail bag 14.

The lower end of the mast 5 is telescoped 70 into the tubular standard 1 and is capable of rotary and vertical movements therein. Rigidly secured to the mast 5 and working in the spiral groove 4 of the cam head 3, is a cam pin or peg 15, the outer end of which is preferably extended far enough to afford a 75 convenient hand-piece.

Pivoted to a bearing 16 secured to the mast 5, at a point above the cam pin 15, is a so-called trigger or trigger-acting lock lever 17, the lower end of which, as shown, is 80 adapted to engage a notch 18 in the cam head 3 when the mast 5 and its arms 6—7 are raised slightly and swung into the position shown in the drawings, with its said arms in position to support the mail bag for delivery 85 to a passing train.

To the upper end of the trigger 17 is secured a buffer block 19 of any suitable material, but preferably of oak. This buffer block 19 is so located that it will be struck 90 by the free end of the pivoted lower arm 7, when the latter is allowed to drop.

The numeral 20 indicates a buffer block of any suitable material, but preferably of oak, and which, as shown, is secured to the brace 95 bracket 9 in such position that it will engage with the free end of the pivoted arm 7 in case said arm should be carelessly thrown upward, thereby preventing the grapple fingers 11 and 12 of said pivoted arm from being 100 thrown against the upper arm 6.

The numeral 21 indicates steps secured to the standard 1, and 21^a indicates steps secured to the mast 5.

The numeral 22 indicates a lantern hook, 105 shown as secured to the mast 5. The mast 5 and arms 6 and 7 are preferably made of wrought iron pipe.

The steps 21 and 21^a permit the carrier to climb up the crane, hang the mail bag on the 110 upper arm, raise the lower arm to a proper position and attach it to the lower end of the

bag. The carrier may then descend to the ground and, by taking hold of the projecting end of the so-called cam pin 15, (which pin serves as an operating lever) easily rotate the mast through approximately 90 degrees and thereby turn the arms 6 and 7 into a position at a right angle to the track, or, in other words, in position to deliver the mail bag to the passing train. Under this rotary movement of the mast, the cam groove 4, acting on said cam pin, raises the mast, its arms 6 and 7 and, of course, the mail bag. In this position the lower end of the trigger or trigger-acting lever engages the notch 18 of the head 3 and thereby locks the mast in its elevated position against rotation and with its arms holding the mail bag, as just stated.

When the passing train takes the mail bag from the arms 6 and 7, the lower end of said arm 7 falls and its free end strikes the head or buffer block 19 of the trigger lever 17 and throws the lower end of said lever out of engagement with the notch 18 of the head 3. The movable section of the crane being thus released, its weight causes it to lower, and the cam groove 4, acting on the cam pin or handle 15, rotates the mast back into a position in which its arms 6—7 stand approximately parallel with the track.

The mail crane above described, while strong and durable, may be cheaply constructed and has no parts that are likely to get out of order. Furthermore, as is above made evident, it may be very easily operated.

What I claim is:

1. A swinging crane comprising a standard, a mast journaled to said standard and provided with a pair of bag-supporting arms, the lower of which is pivoted, a connection between said mast and standard causing said mast to turn when moved vertically, and a trigger-acting lock lever intermediately pivoted to said mast and engageable with said standard, to lock said mast in a raised

position, and which lever is so located that it will be struck by said pivoted arm and released, when said lower arm is dropped, substantially as described.

2. A swinging crane comprising a tubular standard, a mast journaled to said standard and provided with a pair of bag-supporting arms, the lower of which is pivoted, a cam on said standard, a cam pin secured to said mast and coöperating with said cam to cause said mast to turn when moved vertically, and a trigger-acting lock lever intermediately pivoted to said mast engageable with a notch in the upper end of said standard, to lock said mast in a raised position and against rotation, and with its upper end so located that it will be struck by said pivoted arm, and said lever released, when said arm is dropped, substantially as described.

3. In a swinging crane, the combination with a tubular standard, having a spiral cam and a lock notch in its upper end portion, of a mast telescoped into said standard and provided with a pair of bag-supporting arms, the lower of which is pivoted, a pin carried by said mast and coöperating with said cam to cause said mast to turn when moved vertically, the said pin projecting and affording a handle by means of which said mast may be turned, and a trigger-acting lock lever intermediately pivoted to said mast, the lower end thereof being engageable with a lock notch in said standard, to lock said mast in a raised position and against rotation, and with its upper end so located that it will be struck by said pivoted arm, and said lever released, when said arm is dropped, substantially as described.

In testimony whereof I affix my signature in presence of two witnesses.

ALVIN C. McCORD.
